UNITED STATES PATENT OFFICE.

GEORGE J. FRENCH, OF ROCHESTER, NEW YORK, ASSIGNOR TO THE R. T. FRENCH COMPANY, OF ROCHESTER, NEW YORK, A CORPORATION OF NEW YORK.

DESIGN FOR A BOTTLE OR JAR.

46,992.

Specification for Design.

Patented Feb. 23, 1915.

Application filed November 16, 1914. Serial No. 872,480. Term of patent 14 years.

To all whom it may concern:

Be it known that I, GEORGE J. FRENCH, a citizen of the United States, residing at Rochester, in the county of Monroe and State of New York, have invented a new, original, and ornamental Design for Bottles or Jars, of which the following is a specification, reference being had to the accompanying drawing, forming part thereof.

The figure is an elevation of a bottle or jar, showing my new design.

I claim:

The ornamental design for a bottle or jar, as shown.

GEORGE J. FRENCH.

Witnesses:

F. M. ENOS,
A. M. WIXTED.
